UNITED STATES PATENT OFFICE.

GEORGE E. PURPLE, OF LA GRANGE, ILLINOIS, ASSIGNOR TO FLEXIBLE STEEL LACING COMPANY, OF CHICAGO, ILLINOIS, A CORPORATION OF ILLINOIS.

CUTTING DEVICE.

Application filed June 17, 1925. Serial No. 37,692.

This invention relates to cutting devices.

An object of the invention is to provide a cutting device more particularly adapted for cutting belting and other materials, wherein 5 it is necessary to exert powerful pressure upon the cutting blade, in a relatively small and compact device.

Another object of the invention is to provide a cutting device of this character in 10 which a knife blade or cutting tool is arranged to have operative movement in longitudinal and vertical directions upon manipulation of actuating means, said knife being mounted for operative movement upon a 15 support which is held stationary during the cutting operation, and which may be automatically bodily swung to an upraised inoperative position while the belt or other material is being adjusted in the machine, 20 together with safety means for preventing accidental descent of the knife support, and for securing the support in operative position, said means being automatically operable during movement of the actuating 25 means.

Another object of the invention is to provide a cutting apparatus of this character in 30 which means are provided for imparting vertical movement to the knife during its longitudinal movement, said means including a cam arrangement in which anti-friction means are interposed between the cam elements in such a manner that the stresses are transmitted directly through the body 35 portions of the anti-friction elements, in contradistinction to devices in which the anti-friction elements are supported upon pivot pins to which the powerful cutting 40 pressure is transmitted, with a consequent bending or distortion of the pivot pins which interferes with the operation of the apparatus.

Other objects and advantages of the invention will more fully and clearly appear 45 from the description and claims hereinafter following.

In the drawings Figure 1 is a top plan view of the invention, showing the operating handle in raised position, and partially 50 broken away. Figure 2 is a side elevation of the invention, showing the device about to begin the cutting operation. Figure 3 is a vertical longitudinal sectional view of the invention substantially on the line 3-3 of 55 Figure 1, and showing partly in section, and

partially in elevation, the cutting blade and actuating mechanism. Figure 4 is a vertical sectional view similar to Figure 3 showing the knife blade at the limit of its downward cutting stroke. Figure 5 is an end elevational view of the invention. Figure 6 is a side elevational view of the invention, showing the knife support in upraised position. Figure 7 is a transverse sectional view on the line 7-7 of Figure 3; and Figure 8 is 60 a transverse sectional view on the line 8-8 of Figure 3.

The invention broadly comprises a work support A, a knife support or arm B, a knife C, cam means D, actuating means E, locking 70 device F, and safety mechanism G.

The work holder or base A, preferably comprises a horizontally disposed platform 10, the ends of which are preferably formed integrally with end supports 11 and 12, said 75 platform being strengthened by means of a vertically disposed longitudinally extending rib 13 preferably formed integrally with the platform and with the end supports 11 and 12. The support 12 preferably comprises 80 spaced standards 14, the upper inner end surfaces of the standards being rabbeted, as indicated at 15 for the reception of the knife carrying arm B, and a pin 16 is mounted in said standards and extends therebetween, 85 for use in connection with the latch means F on the knife carrying arm B, all of which will be hereinafter referred to. The forward support 11 is also provided with spaced standards 17, and mounted between such 90 standards upon the pivot pin 18, is the knife carrying arm or support B.

The knife carrying support B preferably comprises spaced side members or walls 19 and 20, the wall portion 19 preferably including forward and rear angular extensions 21 and 22 each of which abuts against the inner face of the wall 20, and is secured to such wall by suitable screw bolts 23. Secured to the undersurfaces of the extensions 100 21 and 22, preferably by means of screw bolts 24, are cam blocks 25 and 26, the cam block 25 being provided with an inclined undersurface 27, and the cam block 26 being provided with an inclined surface 28 in 105 a similar manner, the cam blocks 25 and 26 being alike in all respects, and of a width less than the distance between the walls 19 and 20, so as to leave a space 29 between the adjacent face of each cam block and the 110

wall 20. The cam block 25 is provided with a pin 30, and the cam block 26 is provided with a similar pin 31, each of said pins extending transversely therethrough, and projecting into the space 29 at the sides thereof, and upon the end of the pin 30, and of the pin 31, are mounted links 32 and 33 respectively which are connected to the cutting blade C, each of the links 32 and 33 being provided with slots 34 and 35, through which the ends of the pins 30 and 31 project as shown in the drawings, so as to pivotally mount the links upon the blocks, and at the same time permit a certain amount of play in the connections.

The knife C is mounted upon a carrier bar 36, such carrier having a rabbeted portion 37 adapted for the reception of the edge of the blade, the blade being secured to the carrier by means of screw bolts 38, which project outwardly from the blade and move in the runways 38^a provided in the wall 19 of the support B, such runways being cut out as indicated at 38^b to afford access to the bolts 38. Mounted upon the carrier 36 adjacent the ends thereof, and adapted to cooperate with the cam blocks 25 and 26, are oppositely disposed cam blocks 39 and 40, such cam blocks being secured to the carrier 36 by means of screw bolts 41. The cam blocks 39 and 40 have inclined upper faces 42, the inclination thereof corresponding to the inclination of the faces 27 and 28 of the blocks 25 and 26, and such blocks are reduced for the reception of the opposite ends of the links 32 and 33, each of the cam blocks being provided with a pin 42^a which projects through a slot 43 in each of the links 32 and 33. Mounted between the cam surfaces of the cam blocks 25, 26, and 39 and 40 are anti-friction means, which are in the form of rollers 44, each of the rollers being rotatably mounted upon a pin 45, fastened to the links 32 and 33, the rollers 44 being adapted to engage the cam surfaces of the cam blocks, and by reason of the play permitted by the slots 34, 35 and 43, it will be noted that during operation of the device the stresses are transmitted through the body portions of the rollers and not to the pivot pins 45, said pins merely retaining the rollers in position. The carrier 36 is further provided with an inclined guide slot 46^a the walls of which engage a roller 47^a mounted upon a pin 48^a fixedly secured to the wall 20 of the support or frame B, such arrangement acting to raise and lower the blade carrier and support the same during its operation.

The actuating mechanism E for imparting longitudinal movement to the knife and knife carrier, comprises a curved link 46 pivotally connected to the knife carrier 36 by means of a pivot pin 47, the opposite ends of the link 46 being connected to a crank 48 by means of a pivot pin 49, such crank being

mounted upon a pivot pin 50, and the crank in turn is pivotally connected between the arms of a bifurcated lever 51. The lever member 51 is provided with a socket for the reception of a handle 52, by which the lever member 51 is operated, and it will be appreciated that movement of the handle 52 will impart movement to the crank 48, and such movement will be communicated to the knife carrier 36 by the links 46, continued movement of the handle 52 in a counter-clockwise direction causing the lever 51 to come into contact with the end of the support B, and thereafter elevate the said support with reference to the holder 10 as shown in Figure 6.

The automatic locking means F comprises a latch 53, which is pivotally mounted between the side members 19 and 20 on a pin 53^a, said latch being provided with a hooked end 54 adapted to engage the pin 16 between the standards 14, and having at its opposite end a cam surface 55 adapted to engage the surface of an arcuate cam 56 formed upon the link 33, there being a spring 57 connected to the wall of the support B which normally urges the hooked portion 54 out of engagement with the pin 16, the operation being such that when the handle 52 is moved in a counter-clockwise direction, due to the forward travel of the knife carrier, the link 32 will be swung on its pivot causing the latch to be released, and when the lever reaches the position shown in Figure 3, where the lever member engages the end of the support B, the entire knife support B may be elevated to the position shown in Figure 6. When the lever 52 is swung in a cutting direction, the cam 56 by engagement with the cam surfaces 55 of the latch, forces the hooked portion 54 thereof into engagement with the pin 16. When the parts are at the limits of the cutting movement the same may be locked in this position by means of a hooked latch 58, and due to the shape of the support B an offset portion 59 is provided, the lever in its latched position and the offset portion providing a handle 60 by which the entire device may be manually transported from place to place.

The safety means G are provided for the purpose of preventing the accidental descent of the knife support B when the same is in upraised position, such means including a member 61 pivotally mounted at the forward portion of the support B, such member being normally urged in a counter-clockwise direction by means of the spring 62, preferably mounted on the pivot pin 18. The member 61 is provided with a shoulder 63 adapted in certain positions of the parts to be engaged by the adjacent end 64 of the knife carrier 36, the movement of the knife controlling the position of the member 61. The member 61 is adapted to co-operate with a

rib 65 formed at the forward end of the platform 10, such rib being curved to provide a cavity 66, the end portion of the member 61 being inclined as shown at 67 to assure proper movement of the member 61 past the rib 65 during a certain phase of the operation of the device, the construction being such that when the handle 52 is moved sufficiently to tilt the knife carrier B, the spring 62 urges the lower end of the member 61 outwardly, and should the support B accidentally descend, such descent will be checked by engagement of the member 61 with the rib 65, so as to prevent injury to the operator. When the lever 52 is operated to cause intentional descent of the support B, the forward movement of the knife will press the member 61 inwardly so as to clear the rib 65.

In operation when it is desired to cut a piece of material such as belting, assuming the parts to be in the position shown in Figure 4, the latch 58 is disconnected to release the handle 52, which is then swung in an anti-clockwise direction, raising the knife through the action of the crank 48, link 46, and the roller 47^a engaging the inclined surfaces of the guide slot 46^a, such movement bringing the link 33 into an inclined position, causing the cam 56 to ride out of engagement with the cam surface 56 of the locking member F, whereupon the spring 57 will urge the same in an anti-clockwise direction, as shown in Figure 3, to disengage the hooked portion 54 from the pin 16.

Continued movement of the handle 52 in an anti-clockwise direction, due to the engagement of the lever member 51 with the end portion of the support B will cause elevation of the support about its pivot 18, the knife C being entirely retracted between the walls 19 and 20 of the support and the member 61 held in retracted position by reason of the pressure exerted thereon by the knife due to its forward position. Should the support B accidentally descend with the lever in this position there would be no danger to the operator since the knife is entirely retracted between the members 19 and 20 of the support B; however should the handle 52 be operated while the support is in an upraised position, the knife would be projected from within the support B, the projection of the knife due to the arrangement resulting in its rearward movement which releases the member 61, so that should the support fall, the member 61 will come in contact with the rib 65 and prevent further descent. When the support B is in upraised position the material to be cut may be placed upon the platform and the handle 52 operated which will cause the gradual descent of the support B with the handle 52 at the limit of its anti-clockwise movement. During such descent, the member 61 will be held in

its inoperative position by engagement of the knife therewith until it moves past the rib 65. When the support comes to rest upon the rabbeted portions 15 of the standards 14, immediately upon further movement of the lever 52, the cam 28 will engage the cam surface 55 of the latch F, and press the hooked portion 54 thereof into engagement with the pin 16, so that when the knife is performing its cutting operation, the support is securely locked to the platform and can not be detached therefrom during the cutting operation. Further movement of the handle 52 through the crank 48 and links 46 causes further longitudinal movement of the cutter C, and due to the provision of the cam blocks 25 and 26, the interposed rollers 44, and guide means, the knife is caused to descend during the longitudinal movement thereof, and this action continues until the material is cut. In this connection it is pointed out that due to the particular arrangement of the cam blocks and the anti-friction means, the pressure exerted upon the antifriction means is transmitted bodily therethrough with out-bending or distortion of trunnions or pivots upon which the anti-friction means are mounted, which occurs in machines of ordinary construction.

While I have herein shown and described what I now consider the preferred manner of carrying out my invention, the same is merely illustrative, and I contemplate all changes and modifications that come within the scope of the claims appended hereto.

I claim:

1. In a cutting device, the combination with a work holder; of a support provided with cam elements; a cutter provided with cam elements; means for actuating said cutter; and anti-friction elements interposed between the cam elements on said support and on said cutter, said anti-friction means being arranged to transmit the bearing stresses from one cam surface to the other.

2. In a cutting device, the combination with a work holder; a cutter support arranged to be connected to said work holder; cutting means; means for actuating said cutting means toward and from said work holder; and means for automatically disconnecting said cutter support from said work holder upon certain movement of said actuating means.

3. In a cutting device, the combination with a work holder; of a cutter support adapted to be connected to said work holder; cutting means mounted on said cutter support; actuating means for causing advance and retraction of said cutting means with respect to said work holder; and means for automatically disconnecting said cutter support from said work holder upon retraction of said cutting means.

4. In a cutting device, the combination

with a work holder; of a cutter support adapted to be connected to said work holder; cutting means connected to said cutter support; actuating means for operating said cutting means, and for elevating said support with respect to said work holder; means for automatically disconnecting said support from said work holder upon certain movement of said actuating means, and means for preventing the accidental descent of said cutter support.

5. In a cutting device, the combination with a work holder; of a cutter support; cutting means; means for actuating said cutting means to cause advance and retraction thereof; and means for automatically connecting and disconnecting said cutter support with reference to the work holder, dependent upon the advance and retraction of said cutting means.

6. In a cutting device, the combination with a work holder; of a cutter support; cutting means carried by said support; means for advancing or retracting said cutter relative to said work holder, said means being arranged to permit elevation of said support with reference to said work holder; and safety means for preventing accidental descent of said cutter support.

7. In a cutting device, the combination with a work holder; of a cutter support co-operating with said work holder; cutting means carried by said support; means for effecting advance and retraction of said cutting means relative to said work holder, said means being arranged to permit elevation of said cutter support; and safety means for preventing accidental descent of said cutter support, said safety means being arranged to be released by advance of said cutting means while said support is in elevated position.

8. In a cutting device, the combination with a work holder; of a cutter support co-operating with said work holder; cutting means carried by said support; means for effecting advance and retraction of said cutting means relative to said work holder, said means being arranged to permit elevation of said cutter support; safety means for preventing accidental descent of said cutter support, said safety means being arranged to be released by advance of said cutting means while said support is in elevated position, said safety means being arranged to be held in inoperative position during intentional descent of the cutter support.

9. In a cutting device, the combination with a work holder; of a cutter support co-operating with said work holder; cutting means carried by said cutter support; means for advancing and retracting said cutting means relative to said work holder; means for automatically connecting and disconnecting said cutter support with reference to

said work holder dependent upon the direction of movement of said cutting means; and safety means operable to prevent accidental descent of said cutter support.

10. In a cutting device, the combination with a work holder; a cutter support; cutting means carried by said cutter support; actuating means for causing the advance and retraction of said cutting means, said actuating means including inclined bearing members on said support and said cutting means; and anti-friction elements interposed between said bearing members and adapted to transmit the bearing stresses to all of said inclined bearing members.

11. In a cutting device, the combination with a work holder; a cutter support; cutting means carried by said cutter support; actuating means for causing the advance and retraction of said cutting means, said actuating means including inclined bearing members on said support and said cutting means; anti-friction elements interposed between said bearing members and adapted to transmit the bearing stresses to all of said inclined bearing members; and means for connecting and disconnecting said support with respect to said work holder dependent upon the direction of movement of said actuating means.

12. In a cutting device, the combination with a work holder; a cutter support; cutting means carried by said cutter support; actuating means for causing the advance and retraction of said cutting means, said actuating means including inclined bearing members on said support and said cutting means; anti-friction elements interposed between said bearing members and adapted to transmit the bearing stresses to all of said inclined bearing members; means for connecting and disconnecting said support with respect to said work holder dependent upon the direction of movement of said actuating means; and a safety device for preventing accidental descent of said support from an upraised position.

13. In a cutting device, the combination with a work support; a cutter support; cutting means including elements connecting said cutting means and said cutter support; means for imparting longitudinal movement to said cutting means; operating means for advancing and retracting said cutter relative to said work holder during the longitudinal movement of said cutting means, said operating means including inclined bearing surfaces; and anti-friction elements interposed between said bearing surfaces and adapted to transmit the bearing stresses directly through the body portions thereof from one bearing surface to another.

14. In a cutting device, the combination with a cutting blade; of operating means for causing movement of said blade toward

and from the material to be cut, said means including relatively movable parts; and anti-friction elements associated with said operating means and interposed between said movable parts and arranged to transmit the bearing stresses therebetween directly from one to the other.

15. In a cutting device, the combination with a work holder; of a cutter support 10 including spaced walls; inclined bearing blocks mounted between said walls; a cutter provided with inclined bearing blocks; means providing a movable connection between said cutter support and said cutter; anti-friction elements interposed between said bearing blocks; and means for imparting longitudinal movement to said cutter.

16. In a cutting device, the combination with a work holder; of a cutter support; 20 inclined bearing blocks mounted on said support; a cutter provided with inclined bearing blocks; means providing a movable connection between said cutter support and said cutter; anti-friction elements interposed 25 between said bearing blocks; means for imparting movement in a longitudinal direction to said cutter; a latch for connecting said cutter support with said work holder; and cam means associated with said connecting 30 means for detaching said latch from said work holder upon retraction of said cutter.

17. In a cutting device, the combination with a work holder; of a cutter support, inclined bearing blocks mounted on said support; a cutter provided with inclined bearing blocks; means providing a movable connection between said cutter support and said cutter; anti-friction elements interposed 35 between said bearing blocks; means for imparting movement to said cutter in a longitudinal direction; a latch for connecting said cutter support with said work holder; cam means associated with said connecting means for detaching said latch from said work holder upon retraction of said cutter; 40 and a safety member pivotally carried by said cutter support and normally urged to operative position, said safety member being controlled by the position of said cutter.

18. In a cutting device, the combination with a work holder; of a cutter support; cutting means; lost motion link connections between said cutting means and said cutter support, said link connections carrying anti-friction elements operating between said 50 support and said cutting means; and means for actuating said cutting means toward and from said work holder.

In witness that I claim the foregoing I have hereunto subscribed my name this 4th 55 day of June, 1925.

GEORGE E. PURPLE.
